UNITED STATES PATENT OFFICE

155,868

DESIGN FOR A BOTTLE

Julius Braun, Chicago, Ill.

Application December 3, 1948, Serial No. 149,933

Term of patent 14 years

(Cl. D58—8)

To all whom it may concern:

Be it known that I, Julius Braun, a citizen of the United States, residing at Chicago, Illinois, have invented a new, original, and ornamental Design for Bottle, of which the following is a specification, reference being had to the accompanying drawing, forming a part thereof.

In the drawing:

Figure 1 is a front view of a bottle, showing my new design;

Figure 2 is a side view thereof; and
Figure 3 is a bottom view thereof.

I claim:

The ornamental design for a bottle, substantially as shown.

JULIUS BRAUN.
